DESIGN FOR A SHOCK ABSORBER CASING

Bonnie L. Mallory, Cleveland, Ohio, assignor to
Gadget's, Inc., Cleveland, Ohio, a corporation
of Ohio

Application September 12, 1933, Serial No. 49,238

Term of patent 14 years

To all whom it may concern:

Be it known that I, BONNIE L. MALLORY, a citizen of the United States, residing at Cleveland, in the county of Cuyahoga and State of Ohio, have invented a new, original, and ornamental Design for Shock Absorber Casing, of which the following is a specification, reference being had to the accompanying drawing, forming part

thereof, wherein Fig. 1 is a perspective view; Fig. 2 is a top plan view; Fig. 3 is an elevational view and Fig. 4 is an end elevation of my new shock absorber casing.

I claim:—

The ornamental design for a shock absorber casing, substantially as shown.

BONNIE L. MALLORY.
